CLAIM

The ornamental design for an “inflatable pillow”, as shown.

DESCRIPTION

FIG. 1 is a front, bottom and right side perspective view of an inflatable pillow with a lid closed showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a front view of the inflatable pillow of FIG. 1 in a state of gas discharged.

1 Claim, 8 Drawing Sheets
